No. 895,502.

PATENTED AUG. 11, 1908.

W. G. SCHAEFFER.
YIELDABLE DRIVING GEAR.
APPLICATION FILED APR. 10. 1908.

UNITED STATES PATENT OFFICE.

WILLIAM G. SCHAEFFER, OF READING, PENNSYLVANIA, ASSIGNOR TO READING STANDARD COMPANY, OF READING, PENNSYLVANIA, A CORPORATION OF PENNSYLVANIA.

YIELDABLE DRIVING-GEAR.

No. 895,502.

Specification of Letters Patent. Patented Aug. 11, 1908.

Application filed April 10, 1908. Serial No. 426,208.

To all whom it may concern:

Be it known that I, WILLIAM G. SCHAEFFER, a citizen of the United States, and a resident of the city of Reading, in the county of Berks and State of Pennsylvania, have invented 5 certain new and useful Improvements in Yieldable Driving-Gears, of which the following is a specification.

My invention relates to that class of yieldable wheels in which an independently rotatable rim section is frictionally connected by suitable clamping means to an inner wheel section, and more particularly to improvements in the type indicated in my pending 15 application, Ser. No. 401,017, filed November 6th, 1907.

The main objects of my present invention are to more perfectly secure and maintain the proper centering of the separately movable rim section upon the inner section, by providing for a satisfactory connection between the sections independently of the frictional clamping means heretofore employed; and also to so improve the frictional connection 20 between the sections as to insure more satisfactory operation and reduced labor and cost for maintenance.

The invention is fully described in connection with the accompanying drawings and its 30 novel features are specifically pointed out in the claims.

Figure 1 is a cross-sectional view, on the line 1—1 of Fig. 2, of a complete wheel embodying my improvements. Fig. 2 is a face 35 view of the same, a portion of one clamping plate being broken away to show the junction of the sections. Fig. 3 is a cross-section of the independently connected wheel sections, before the frictional clamping means 40 shown in Fig. 1 are applied thereto.

In the drawings *a* represents an inner wheel section of circular form, provided as shown with a central screw-threaded opening *b* for securing the same to a shaft; *c* is the 15 outer or rim section rotatably mounted upon the periphery of the inner section *a*; *d d* are oppositely arranged annular clamping plates covering the circular junction of the sections; and *e* are clamping bolts passed transversely 20 through the plates *d d* and inner section *a*; these elements being similar in general form and arrangement to those shown in my prior application referred to, but differing therefrom in important features as hereafter described.

In my prior construction the rim section *c* is centered upon and rotates on the periphery of the inner section *a*, but the two sections, being connected only through the frictional clamping means, are held only by the latter, and are liable in practice to be slightly displaced and subjected to strains which tend to vary the uniform frictional resistance intended to be provided by the clamping means, and to necessitate attention which it is highly important to avoid. In overcoming these difficulties I provide in the first place for independently connecting the two sections in proper relative position, this being accomplished as shown by providing race-grooves in the opposed peripheries *a' c'* of the two sections, into which a series of anti-friction balls *f* is introduced, one at a time, through a suitable lateral opening *f'*; said balls, when in place, serving to connect the 60 outer section *c* to the inner section *a* in proper concentric and lateral positions, while at the same time insuring easy rotation of one section upon the other. With the sections thus independently connected the 65 function of providing uniform frictional resistance to the rotary movement of one section upon the other is provided for as follows: The annular clamping plates *d d*, which are preferably made of hard bronze 70 metal adapted for direct frictional contact with the movable wheel section *c*, are formed with flanges *d'* at their inner peripheries and are accurately bored to fit upon circular shoulders or offsets *a' a'* formed upon the 75 opposite faces of the section *a*. The outer portions of the plates which overlap the rim section *c*, are each provided on their inner faces, as shown, with an annular friction projection or bead *d'* adapted to fit a corresponding annular recess *c'* in the opposing rim-section face. The two plates *d d* are 80 rigidly connected to the inner section *a* by the transverse clamping bolts *e*, and are at the same time pressed into frictional engagement with the rim section *c* to provide proper frictional resistance to separate rotary movement of the latter. Provision is made for 85 proper lubrication by forming grooves *d'* in the contacting friction surfaces, connecting 90 with the chambers *g* formed between the plates and the wheel sections, to which chambers the lubricant may be introduced 95 through a suitable opening *h*.

The advantages of my improved construc- 110

tion as previously pointed out will be readily seen, and the preferred construction specifically shown and described may be modified within the spirit of my invention.

5   What I claim is:—

1. A wheel comprising a circular inner section, a separately rotatable rim section and anti-friction balls entered in opposing peripheral race-grooves in said sections, oppositely arranged annular clamping plates covering the circular junction line of the two sections, and transverse clamping bolts whereby one of said sections is rigidly connected to said plates and the other section yieldingly connected thereto by frictional engagement with the overlapping portions of the plates substantially as set forth.
2. A wheel comprising a circular inner section, a separately rotatable rim section and anti-friction balls entered in opposing peripheral race-grooves in said sections, oppositely arranged annular clamping plates covering the circular junction line of the two sections and having flanged inner peripheries fitted upon circular offsets on the opposite faces of the inner section, and transverse clamping bolts rigidly connecting said inner section to said plates, the meeting faces of the outer section and of the plate portions overlapping said section being provided with annular projections and grooves adapted to provide frictional connection between them substantially as set forth.
- 25   20   15

connected to said plates and the outer section yieldingly connected to the same by frictional engagement with the portions 30 thereof overlapping said outer section substantially as set forth.

3. A wheel comprising a circular inner section, a separately rotatable rim section and anti-friction balls entered in opposing peripheral race-grooves in said sections, oppositely arranged annular clamping plates covering the circular junction line of the two sections and having flanged inner peripheries fitted upon circular offsets on the opposite 35 faces of the inner section, and transverse clamping bolts rigidly connecting said inner section to said plates, the meeting faces of the outer section and of the plate portions overlapping said section being provided with 40 fitted annular projections and grooves adapted to provide frictional connection between them substantially as set forth.

In testimony whereof, I affix my signature, in the presence of two witnesses.

WILLIAM G. SCHAEFFER.
